FUEL SAVING DEVICE FOR OIL HEATERS

John Carlise, New York, N. Y.

Application June 18, 1942, Serial No. 447,538

5 Claims. (Cl. 110—97)

1

This invention relates to new and useful improvements in a fuel saving device for oil burners. More particularly, the invention proposes the provision of a heat retaining member supported within the housing of an oil burner which has a top vent and a burner at the bottom portion, for the purpose of receiving and holding heat given off by the burner and so preventing the rapid passage of heat through the housing. With this construction the burner may be constructed of smaller capacity than heretofore, and yet sufficient heat will be given off to suitably heat a house. It has been found that with the new construction a one wick burner may be used in place of the ordinary two wick burner now being used.

Furthermore, it has been found that with the new construction less fuel is required. An experiment was made in the room of a small house, of a size 12' x 16' and 9' 4" high, and it was found that with the new construction three gallons of fuel were required in 24 hours, while with the old construction five gallons were required in 23 hours to maintain the room at identical temperatures.

Still further the invention proposes a construction of heat retaining member formed of a plurality of laminations which may be slightly separated when desired to increase the heat discharge of the retaining member when more heat is required.

For further comprehension of this invention, and of the objects and advantages thereof, reference will be had to the following descriptions and accompanying drawing, and to the appended claims in which the various novel features of the invention are more particularly set forth.

In the accompanying drawing forming a material part of this disclosure—

Fig. 1 is a perspective view of an oil burner having a fuel saving device constructed in accordance with this invention.

Fig. 2 is a side view of Fig. 1 with portions broken away to disclose interior parts.

Fig. 3 is a plan view of the burner shown in Fig. 2, this view being taken looking in the direction of the line 3—3 of Fig. 2.

Fig. 4 is a fragmentary enlarged detailed view of a portion of Fig. 2.

Fig. 5 is a perspective view of certain of the parts shown in Fig. 4 with parts being broken away for clarity of illustration.

Fig. 6 is a fragmentary sectional view taken on the line 6—6 of Fig. 4.

Fig. 7 is an enlarged partial elevational view 55

looking in the direction of the line 7—7 of Fig. 6.

The fuel saving device for oil burners, in accordance with this invention, is used in combination with an oil burner 10 having a hollow housing 11 with a top vent 12 and a fuel burner 13 in the bottom portion thereof, and the usual air circulation system not shown. The top vent 12 is provided with the usual automatic draft regulating swing gate 12^a and adjacent manually operable valves 12^b, one at each side of the draft regulating swing gate 12^a, to circulate the heat most effectively. This fuel burner 13 is illustrated having only one circular wick 14, about seven inches in diameter which may burn with a high flame during the day and with a low flame during the night to produce the desired heat. The new device includes a horizontally laminated heat retaining member 15 supported within the housing 11 above said burner 13 and adapted to receive and hold heat given off by the burner to prevent the rapid passage of heat through the housing.

Heretofore, without the provision of the heat retaining member 15 the heat from the burner 25 would rapidly pass through the hollow housing and out of the vent 12.

The heat retaining member 15 comprises a plurality of horizontal laminations 16, 17 and 18 which are supported upon a pair of angle members 19 attached on the sides of the housing 11. Headed studs 20 are mounted on the ends of the angle members 19 and pass through aligned openings 21 formed in the laminations 16, 17 and 18. Springs 22 are coaxially mounted upon the 35 stud 20 and act between the heads of the studs and the top lamination for holding the laminations downwards in intimate contact with each other.

A pair of laterally spaced strips 23 are fixedly 40 attached by screws 24 to the ends of the top lamination 16. Pins 25 project from the laminations 17 and 18 and engage in vertical slots 26 formed in the strips 23. The arrangement is such that the top lamination 16 may be lifted for slightly 45 separating the laminations 16, 17 and 18, the pins 25 engaging the bottoms of the slots 26 to control the amount of separation of the laminations.

The top lamination 16 is provided with several lugs 28 which are engaged by flexible members 50 29 extended upwards and engaged over pulleys 30 on a shaft 31. This shaft 31 projects from the front of the housing 11 and is provided with a handwheel 32 by which the shaft may be turned. The handwheel 32 has a back peg 33 which may engage in one of a plurality of open-

ings 34 formed in the housing 11 concentric with the shaft 31 for holding the shaft in various turned positions. A spring 35 acts between one of the pulleys 30 and one side of the housing 11 for urging the shaft 31 in one direction to maintain the engagement of the peg 33 with one of the openings 34.

The operation of the device is as follows:

Normally, the laminations 16, 17 and 18 are in face contact with each other. The heat from the burner 13 is readily absorbed and held by these laminations which are constructed of cast iron or other suitable substance. During the use of the oil burner the retained heat will be slowly radiated and will be directed in the usual way to the compass of the room. If it is desired that additional heat be drawn out from the heat retaining member 15 and discharged into the room, it is merely necessary to grip the handwheel 32, pull the hand wheel 32 outwards to disengage the peg 33 from its opening 34, and then turn the shaft 31 for causing the pulleys 30 to draw up the flexible members 29. This will lift the top lamination 16 and indirectly lift the second lamination 17 and so separate the laminations from each other. Now more radiating surfaces are exposed to the air currents.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A fuel saving device, comprising a housing for the passage of heat and having spaced side walls, horizontal support members mounted on said side walls, a laminated heat retaining member rested on said support members, vertical headed studs extending from said support members and slidably extended through complementary openings formed in the layers of said heat retaining member limiting movement of said layers relative to each other to the vertical only, means for lifting the top layer of said heat retaining member, spaced vertically extending strips having their top ends securely attached to opposite sides of the top layer and their free ends projected downwards along opposite sides of the bottom layers of said heat retaining member and formed with spaced vertically extended elongated slots aligned with the edges of said bottom layers, and pins from said bottom layers engaging said vertical slots, said slots for said bottom layer being slightly longer than the slots for the next layer above, whereby when said top layer is lifted each of said bottom layers will be successively lifted and spaced from each other.

2. A fuel saving device, comprising a housing for the passage of heat and having spaced side walls, horizontal support members mounted on said side walls, a laminated heat retaining member rested on said support members, vertical headed studs extending from said support members and slidably extended through complementary openings formed in the layers of said heat retaining member limiting movement of said layers relative to each other to the vertical only, means for lifting the top layer of said heat retaining member, spaced vertically extending strips having their top ends securely attached to opposite sides of the top layer and their free ends projected

downwards along opposite sides of the bottom layers of said heat retaining member and formed with spaced vertically extended elongated slots aligned with the edges of said bottom layers, and pins from said bottom layers engaging said vertical slots, said slots for said bottom layer being slightly longer than the slots for the next layer above, whereby when said top layer is lifted each of said bottom layers will be successively lifted and spaced from each other, and expansion springs mounted on said studs and operating between the heads of said studs and the adjacent faces of the topmost layer of said heat retaining member for urging the layers into facial contact with one another against the action of said lifting means.

3. A fuel saving device, comprising a housing for the passage of heat and having spaced side walls, horizontal support members mounted on said side walls, a laminated heat retaining member rested on said support members, vertical headed studs extending from said support members and slidably extended through complementary openings formed in the layers of said heat retaining member limiting movement of said layers relative to each other to the vertical only, means for lifting the top layer of said heat retaining member, spaced vertically extending strips having their top ends securely attached to opposite sides of the top layer and their free ends projected downwards along opposite sides of the bottom layers of said heat retaining member and formed with spaced vertically extended elongated slots aligned with the edges of said bottom layers, and pins from said bottom layers engaging said vertical slots, said slots for said bottom layer being slightly longer than the slots for the next layer above, whereby when said top layer is lifted each of said bottom layers will be successively lifted and spaced from each other, said support members comprising angle members having one of their arms securely attached to said side walls and their free arms directed inwards and provided with said studs.

4. A fuel saving device, comprising a housing for the passage of heat and having spaced side walls, horizontal support members mounted on said side walls, a laminated heat retaining member rested on said support members, vertical headed studs extending from said support members and slidably extended through complementary openings formed in the layers of said heat retaining member limiting movement of said layers relative to each other to the vertical only, means for lifting the top layer of said heat retaining member, spaced vertically extending strips having their top ends securely attached to opposite sides of the top layer and their free ends projected downwards along opposite sides of the bottom layers of said heat retaining member and formed with spaced vertically extended elongated slots aligned with the edges of said bottom layers, and pins from said bottom layers engaging said vertical slots, said slots for said bottom layer being slightly longer than the slots for the next layer above, whereby when said top layer is lifted each of said bottom layers will be successively lifted and spaced from each other, said pins when said layers are in face contact being located within the top ends of said slots to move to the bottom thereof when said layers are lifted for holding the layers with their adjacent faces spaced.

5. A fuel saving device, comprising a housing for the passage of heat and having spaced side walls, horizontal support members mounted on said

side walls, a laminated heat retaining member rested on said support members, vertical headed studs extending from said support members and slidably extended through complementary openings formed in the layers of said heat retaining member limiting movement of said layers relative to each other to the vertical only, means for lifting the top layer of said heat retaining member, spaced vertically extending strips having their top ends securely attached to opposite sides of the top layer and their free ends projected downwards along opposite sides of the bottom layers of

said heat retaining member and formed with spaced vertically extended elongated slots aligned with the edges of said bottom layers, and pins from said bottom layers engaging said vertical slots, said slots for said bottom layer being slightly longer than the slots for the next layer above, whereby when said top layer is lifted each of said bottom layers will be successively lifted and spaced from each other, said heat retaining member having its layers formed of cast iron.

JOHN CARLISE.
